Application March 31, 1944, Serial No. 528,821

2 Claims. (Cl. 143—132)

1

This invention relates to attachments, for machines employing a tiltable table top, designed to release and secure the tilting means.

Up to the present time certain machines employing a tiltable table top designed to tilt in two directions and employing a nut and bolt combination for locking the table against tilting after it has been swung to desired predetermined position have been employed. When, however, a structure of this kind is swung to be locked in a tilted position sloping downwardly over the locking nut, it is difficult to reach the latter and in some cases practically impossible to do so. Consequently, by using an ordinary wrench or a known special tool to accomplish this locking function it is very difficult to get at the locking nut and in some positions of the table, practically impossible.

These difficulties are avoided in the present invention.

It is therefore an object of the present invention to provide a special attachment, for machines employing a tilt top table, which may be employed to lock the table in its desired adjusted position regardless as to what angle it may be desired to swing and secure the table.

A further object of the invention is to provide an attachment of this kind which will always be positioned ready to hand and therefore can be operated with facility.

A still further object of the invention is to provide an attachment of this kind which, will be maintained in position in engagement with the locking nut or which may be disengaged therefrom and employed as a special tool for tightening or loosening other nuts on the machine of a size corresponding to the socket of the attachment.

With these and other objects in view the invention generally comprises an attachment, for machines having a tiltable top, which employs a shank having a swingably mounted socket at one end and an operating member at the other projecting beyond the table edge, a holding bracket on the tiltable top normally holding said shank and means cooperating between the shank and the bracket for retaining the socket in engagement with the securing nut of the machine. The bracket is formed preferably so as to permit detachment of the shank from mounted position and also to permit ready mounting thereof, the shank, when mounted in a bracket, being swingable with the table as it is swung to various tilted positions desired.

The invention will be clearly understood by reference to the following detailed specification

2

taken in conjunction with the accompanying drawing.

In the drawing:

Figure 1 is a fragmentary view of the tiltable table top of a machine illustrating the attachment according to the present invention in mounted position and in engagement with the securing nut controlling the setting of the table top in adjustable position.

Figure 2 is an enlarged sectional fragmentary detail of part of Figure 1.

Figure 3 is a fragmentary sectional view of Figure 1 taken substantially along the line 3—3 of Figure 1, and

Figure 4 is a transverse section taken substantially along the line 4—4 of Figure 1.

Referring to the drawing:

A indicates the tilting top of a machine which, for instance, may employ a band saw B passing through the table top A, the latter being tiltable in two directions by means of suitable pivots such as the pivotal axis 10, indicated in Figure 1, and the pivotal axis represented by the bolt 11 (illustrated most clearly in Figure 3). The pivoting or tilting movement of the table in respect to the bolt 11 is effected by the fitting C which employs the quadrant plate 12, carrying the pin or bolt 11 which projects from one surface thereof and is designed to pass through the arcuate slot 13 in the bifurcated mounting piece 13a (Figures 1 and 3). The swing adjustment of the table top A, in terms of the pivotal axis represented by bolt 11, is effected by tightening or loosening as the case may be, the nut 14 on the bolt 11 so that the table top may be swung to a predetermined desired position when the nut 14 is loosened and retained in that position when the nut 14 is tightened.

Tilting of the table in the opposite direction about the pivotal axis 10 is accomplished by including in the fitting C, the spaced, parallel, substantially arcuate arms 15 which in fact carry the pivot pins 10, the latter being pivotally mounted in the table in any suitable manner such, for instance, as illustrated in Figure 3. Control of the adjustment of the table top when swung about the pivot pins 10 is effected by means of a bolt or the like 16 projecting from the arms 15 and passing through arcuate slots 17, formed in adjacent bracket plates 18. By tightening or loosening the nut 19 in each case, swinging of the table top A is permitted in this direction as well as its securing in the desired position.

In the case of a machine such as the kind illustrated in the present drawing, the band saw B

passes through slots in the table (not shown) and the table swings relatively to the band saw which latter may pass through a suitable guide 29 mounted on one side of the mounting piece 13a.

In order to control the tightening and loosening of the securing nut 14 which is a main control nut, I provide a socket wrench 21 which by way of a universal joint action 22 is fastened to the shank 23, forming the body of the tool or attachment which has a suitable operating handle or the like 24, such as a ratchet handle. The shank 23 is of such length that it extends from the socket 21 to a point beyond the edge of the tilting table top A of the machine and thus is accessible at the edge of this table.

To mount the shank 23 I provide a bracket 25 which is preferably bifurcated to form the two arms 26 and 27 (see Figure 4) formed by the central slot 28. A securing member or pin 29 is designed to traverse the slot 28 and is moved to and from its normal securing position, such as by means of screw threading 30 and the operating handle 31. Thus when the socket wrench portion 21 of the attachment is engaged on the securing nut 14 the attachment may be swung upon the universal joint so that the shank passes up into the slot 28. The pin 29 may then be caused to traverse the slot 28 by screwing it into position and the shank 23 is therefore fastened in the bracket 25.

In order to retain the socket portion 21 of the attachment in operative relationship to securing nut 14 I provide on the shank 23 a coil spring 32. This at one end is designed to abut a suitable stop member 33 which may take the form of a collar, and at the other end the coil spring is designed to abut a suitable shoe 34 which is preferably formed with a cam like surface 35. Thus when the socket portion has been engaged with the securing nut 14 and the shank is then swung from the dotted line position shown in Figure 2 to the full line position, slight pressure inwardly upon the coil spring 32 by way of the shoe 34 will cause the shoe to engage the inwardly directed surface of the bracket 25 which thus tends to exert a slight pressure upon the coil spring and thereby retains the socket portion 21 in positive engagement with the securing nut 14.

With the attachment thus mounted it is manifestly clear that when the table is tilted in any direction the operating member 24 for the shank 23 will always be readily accessible. In this connection it should be noted that the upper end of the slot 28 is defined by the curved formation 36 which together with the amount of clearance permitted between the top of the shank 23 and the surface 36 permits all necessary relative movement between the upper end of the slot and the shank when the table is tilted in a direction toward or away from the shank.

As an illustration of the general utility of the attachment let us assume that the table A is tilted so that the right hand edge shown in Figure 1 is moved downwardly to its extreme degree of travel. In assuming this position the belt 37 driving the pulley 38 will of course move with the table and any slackening in the belt 37 will be taken up by suitable taking up mechanism. At the same time the shank 23 will swing downwardly with the table top through the pivot facilities provided by the universal joint 22, and when the table has reached its adjusted position the handle 24 of the attachment will still be at the

outer edge of the table and readily accessible. There is no problem, therefore, presented when using such an attachment as is the case in such a situation where it is necessary by means of a wrench of any desired shape to get in under the tiltable top to tighten the securing nut 14.

In addition to providing a most convenient means for loosening and tightening the securing nut 14 the manner in which the attachment is applied readily lends itself to further utility. For instance, the attachment may readily be demounted from the bracket 25 by merely removing the pin 29 and swinging the shank 23 to the dotted line position of Figure 2 whereupon it may be pulled away from the nut 14. Thus in the case of other nuts on the machine such as the nuts 19, which are all of a size similar to the securing nut 14 the attachment may be used as a special nut tightening or loosening tool.

From the foregoing it is apparent that I have provided a useful attachment for machines employing a tiltable top whereby is facilitated the adjustment of such table tops regardless of the manner in which they may be tilted.

What I claim as my invention is:

1. In a machine employing a table top mounted on its frame to tilt in all directions and including a screw securing means adjacent the tilting point for securing said top in adjusted position, an adjusting member for loosening or tightening said securing means including a shank, a head pivotally connected to said shank at one end to swing in all directions and engageable with said securing means, the opposite ends of said shank extending adjacent to one edge of said table top, a bifurcated bracket mounted adjacent the edge of said table top having parallel arms spaced apart from one another, said shank being receivable between said arms and swingably movable therebetween, a detachable pin member traversing said arms and said space therebetween to retain said shank in said bracket, said pin being removable to detach said shank, and operating means connected with said shank, said pin retaining said operating means in accessible position adjacent the edge of said table top regardless of the angular position of the latter.

2. The combination with a machine employing a table top mounted on its frame to tilt in all directions and including a screw securing means adjacent the tilting point for securing such top in adjusted position, of an adjusting member for loosening or tightening said screw securing means, including a shank and a head, the latter being connected to one end of the shank by a universal joint, said head being engageable with said securing means, the opposite end of said shank extending adjacent to one edge of said table top, means for detachably mounting said shank in relatively movable relation to said table top and swingable therewith, including a bifurcated bracket carried on the table top designed to receive the shank and detachable securing means for retaining said shank in mounted position, a coil spring, anchored on said shank, engageable with said mounting means and compressible by the latter to retain said head in positive engagement with said screw securing means and operating means on said shank in accessible position adjacent the edge of said table top regardless of the angular location of the latter.
